UNITED STATES PATENT OFFICE.

FRANK BUCHANAN, OF SYRACUSE, NEW YORK.

DESIGN FOR A STREET TRAFFIC SIGNAL.

Application filed March 12, 1925. Serial No. 12,699. Term of patent 14 years.

To all whom it may concern:

Be it known that I, FRANK BUCHANAN, a citizen of the United States, residing at Syracuse, in the county of Onondaga, and in the State of New York, R. F. D. No. 1, have invented a new, original, and ornamental Design for Street Traffic Signal, of which the following is a specification, reference being had to the accompanying drawing forming part thereof.

In the drawing the figure is a perspective

view of a traffic signal embodying my new design.

I claim:

The ornamental design for a street traffic signal, substantially as shown.

In testimony whereof, I have hereunto signed my name, at Syracuse, county of Onondaga, and State of New York, this 16th day of February, 1925.

FRANK BUCHANAN.
